ABSTRACT

A closure for a container characterized by a top entry for a prying tool which fractures a portion of the closure for the removal thereof from the container and which provides a tamper-proof arrangement for customer assurance.

CLOSURE

As is known, the use of aerosol type products is very widespread. One source of problem, however, is to assure the user that the product container has not already been in use prior to purchase. While there have been various approaches towards a tamper-proof closure, most have been awkward to manufacture and cumbersome for the user.

The invention represents simplicity, as well as highly effective performance, in tamper-proof closures for a conventional aerosol product container. Briefly, the closure is defined by a top wall and a depending outer wall, the latter typically being circular in configuration. An inner wall or skirt, concentric with the outer wall, is adapted to be received beneath a portion of the cap on the product container, where the tolerances make a secure fit and one which prevents the closure from being removed without the provisions of the invention.

In this latter connection, a passageway is defined along the inner surface of a portion of the aforesaid skirt, by the sides of which are slots. The passageway opens to the top wall of the closure, where a fracturable membrane may cover the opening. In order to remove the closure from the product container, a screw driver or a prying device, for example, fractures the membrane and is moved downwardly into the passageway. With the angling of the screw driver, in a pivot-like manner, towards the outer wall of the closure, the inner wall is fractured, releasing the inner wall from its secured relationship with the cap on the product container. The preceding is in contrast to prior arrangements which involved bending or flexing action. Provision may also be made as to releasably securing the outer wall of the closure to the product container.

A better understanding of the principles of the invention will become more apparent from the following description, taken in conjunction with the accompanying drawings, wherein:

FIG. 1 is a perspective view, partly broken away, showing a closure in accordance with the invention;

FIG. 2 is a view in vertical section of the closure, showing the aforesaid passageway at the right thereof;

FIG. 3 is a top plan view of the closure of the invention;

FIG. 4 is a view of the closure in vertical section, taken at line 4—4 of FIG. 3 and looking in the direction of the arrows;

FIG. 5 is a bottom plan view of the closure;

FIG. 6 is a fragmentary perspective view showing a portion of the closure after fracturing has been accomplished; and,

FIG. 7 is a fragmentary view, partly in vertical section, showing an alternative closure arrangement.

For the purposes of promoting an understanding of the principles of the invention, reference will now be made to the embodiments illustrated in the drawings and specific language will be used to describe the same. It will nevertheless be understood that no limitation of the scope of the invention is thereby intended, such alterations and further modifications in the illustrated devices, and such further applications of the principles of the invention as illustrated therein being contemplated as would normally occur to one skilled in the art to which the invention relates.

Referring now to the figures, the closure 10 defining the invention comprises a top wall 10a having a depending outer wall 10b and a depending skirt or inner

wall 10c concentric with such outer wall 10b. A passageway 12 is defined on a portion of the inner surface of inner wall or skirt 10c, being formed by walls 12a, 12b and 12c. The bottom of the passageway 12 is typically open. A portion 10f of the inner wall or skirt 10c serves as the fourth wall of passageway 12. Slots 14, in inner wall 10c, extend adjacent walls 12a and 12c of the passageway 12. As should be apparent from FIGS. 1 and 4, the slots 14 do not extend the full length of inner wall 10c.

An entry 10d is provided on the top wall 10a of the container 10 and may, if desired, be closed, prior to use, by a fracturable membrane 10e. It might be noted that closure 10 may be typically made from a linear polyethylene resin through an injection molding process.

With reference now to FIG. 2, a typical aerosol product container 20 is shown, generally identifiable by a product dispensing valve 20a, an upper ring-like portion 20b, and a semi-spherical portion 20c extending to the body 20d of the container 20. A recessed portion 20e extends between portions 20b and 20c of the container 20, such being adapted to receive a small bead 10g on the free edge of the inner wall 10c. Typically, the outer wall 10b of the closure 10 extends into a recessed portion 20f around the periphery of the container 20 adjacent the body 20d thereof. It should be understood that tolerances and the geometry of the overall configuration prevent the removal of the closure 10 from the product container 20 without the use of a prying member.

FIG. 7 shows an alternative arrangement wherein the container 20 includes a rim 20g adapted to lockingly receive a groove 10g' in the inner surface of the outer wall 10b, where the remaining structure is as described above. In another arrangement, the outer wall 10b of the closure 10 could merely overhang the top of the body 20d of the product container 20, i.e. with no locking function.

In use, a screw driver or other prying member (not shown) is inserted through the membrane 10e and into passageway 12. Thereafter, through pivotal action of the screw driver towards the outer wall 10b, the inner wall or skirt 10c is fractured (see FIG. 6), permitting release and removal of the closure 10. In other words, the original secure fit no longer exists. Closure 10 can be readily removed and, later, returned to a covering, but not locked, position.

It should be apparent, therefore, that with the invention the customer for the product knows that the product has not been used if either (a) the membrane has not been broken, or (b) if there is no membrane, the portion of the inner wall or skirt has not been fractured, the latter being true in either instance. A major object of the invention is the provision of a tamper-proof closure, in contrast to what might be termed a child-proof closure, where the latter typically locks into position after use and requires release by flexing action or bending action, although the embodiment of FIG. 7 would provide such two-fold function.

The closure described herein is susceptible to various changes within the spirit of the invention, as, for example, in proportioning or the like. Thus, the preceding should be considered illustrative, and not as limiting the scope of the following claims:

We claim:

1. A closure for a container having a recessed portion at the dispensing end thereof comprising a top wall, an outer wall, and an inner wall concentric with and spaced apart from said outer wall, said inner wall having a portion adapted to be received in said recessed portion of said container, a passageway extending from said top wall along said inner wall, and partially extending slots in said inner wall adjacent portions of said passageway, said passageway being defined by a first wall, a second wall, a third wall and a portion of said inner wall, and where said slots extend adjacent said first wall

and said third wall outside of said passageway.

2. The closure of claim 1 where said passageway has a fracturable member closing the opening thereto.

3. The closure of claim 1 where said container has another recessed portion at the dispensing end thereof, and where said outer wall has a portion adapted to be received in said another recessed portion.

4. The closure of claim 1 where said outer wall and said container have cooperating locking portions.
